QFS. 1966

Robert Dunn, of Greenpoint, N.Y.

Letters Patent No. 1966 Dated June 28, 1864.

Design for a Clock Case.

The schedule referred to in these letters Patent and making part of the same

Is as follows:

Be it known that I, Robert Dunn, of Greenpoint, in the County of Kings and State of New York, have invented a new and ornamental Design for Clock Case; and I do hereby declare that the following is a full, clear and exact description thereof, which will enable others skilled in the art to make and use the same, reference being had to the accompanying drawings making part of this specification.

Fig. 1 is a front elevation of this design.

Fig. 2 is a transverse vertical section of the same.

Similar letters of reference indicate like parts.

This invention consists in a clock case with a circular face ornamented by a series of beads and supported by pilasters which rise from the base on the sides of an open field, the central portion of which is occupied by a beaded capital in such a manner that a case is produced of a novel and ornamental appearance.

A represents the circular face which is surrounded by the beaded ring a. The inner or central space of the face A is occupied by the door b. which consists of a beaded ring of the form as clearly shown in the drawing. The outside diameter of the door is somewhat smaller than the inside diameter of the ring a, leaving a flat space, c, surrounding said door.

The ring a, is supported by two pilasters d, d, which rise from the base B, on the sides of the open field C. Said pilasters are ornamented

DES 1966

21 by beads e, near their top, and by bastions f at their bottom, and the space between the beads and bastions is occupied by spear-shaped projections g, having their sharp pointed ends turned up and their dull pointed down, as clearly shown in Fig. 1. of the drawing.

The space at the bottom and in the middle of the field is occupied by the cyma i, which is composed of a series of mouldings commencing on the top with the bead h which rests on the scotia j, and the scotia joins the fillet k which rises from the bastion or torus l, and this torus is supported by the fillet l.

The base B is composed of a bead m, which is supported by the scotia n, and this scotia rises from the fillet o which is supported by the torus p. This torus rises from the fillet q which is supported by the cyma r rising from the corona s. The corona is bordered below by the bead t, and this bead rests in the scotia u, which is supported by the fillet v, and this fillet is joined by the torus w.

By this combination of mouldings a very rich and ornamental base is produced, which gives to the case a beautiful finish.

Having thus described my invention, I claim as new and desire to secure by Letters Patent.

The design for a clock case as herein shown and described.
